US00D995136S

(12) United States Design Patent (10) Patent No.: US D995,136 S
Pedersen (45) Date of Patent: * Aug. 15, 2023

(54) CHAIR

(71) Applicant: Houe ApS, Ry (DK)

(72) Inventor: Henrik Pedersen, Aarhus C (DK)

() Term: 15 Years

(21) Appl. No.: 35/513,957

(22) Filed: Feb. 25, 2022

(80) Hague Agreement Data

Int. Filing Date: Feb. 25, 2022

Int. Reg. No.: DM/219716

Int. Reg. Date: Feb. 25, 2022

Int. Reg. Pub. Date: Apr. 1, 2022

(51) LOC (14) Cl. 06-01

(52) U.S. Cl.

USPC D6/370

Primary Examiner — Mimosa De

(57) CLAIM

I claim the ornamental design for a chair, as shown and described herein.

DESCRIPTION

1.1 : Perspective

1.2 : Right

1.3 : Front

1.4 : Left

1.5 : Top

1.6 : Back

1.7 : Bottom

Fig. 1.1 shows a perspective view of the chair; Fig. 1.2 shows a right side view of the chair; Fig. 1.3 shows a front view of the chair; Fig. 1.4 shows a left side view of the chair; Fig. 1.5 shows a top view of the chair; Fig. 1.6 shows a back view of the chair; Fig. 1.7 shows a bottom view of the chair.

1 Claim, 7 Drawing Sheets
